UNITED STATES PATENT OFFICE.

EMIL J. FRANCK, OF PHILADELPHIA, PENNSYLVANIA.

FASHIONING KNITTING-MACHINE.

1,046,764.

Specification of Letters Patent. Patented Dec. 10, 1912.

Application filed August 30, 1905. Serial No. 276,371.

To all whom it may concern:

Be it known that I, EMIL J. FRANCK, a citizen of the United States, residing at Philadelphia, in the county of Philadelphia and State of Pennsylvania, have invented certain new and useful Improvements in Fashioning Knitting-Machines, of which the following is a specification.

One object of the present invention is to provide for increasing the diameter of a knitted tube during its manufacture, or more specifically to produce a seamless widened leg as for stockings.

Another object of the invention is to provide a circular machine for producing the character of work mentioned.

Another object of the invention is to cause said machine to operate automatically and to occupy a comparatively small space, and another object of the invention is to provide a circular knitting machine such as is used for producing seamless hosiery with compact, efficient and reliable means for widening the legs of such hose.

To these and other ends hereinafter set forth the invention comprises the improvements to be presently described and finally claimed.

The nature, characteristic features and scope of the invention will be more fully understood from the following description taken in connection with the accompanying drawings forming part hereof and in which—

Figure 1, is a view taken in central section and illustrating a machine embodying features of the invention. Fig. 2, is a top or plan view of the same. Fig. 3, is an elevational view of a detail of construction, and Fig. 4, is a diagrammatic view illustrating the needles.

In the drawings 1, may be taken to be the ordinary circle of latch needles and 2, are a set or group of what may be called widening needles and they are arranged intermediate of some of the needles 1 and are reciprocated at an angle with or inclination to the line of reciprocation of the needles 1. The circle of needles 1, produce a tubular fabric in the ordinary way and the widening of this tubular fabric is effected by bringing the needles 2 successively in proper order into action in such a way that they cooperate with the needles 1 and when the needles 2 are in action the work at the portion of the circle where the widening is go-

ing on occupies what may be called a zig-zag line; that is to say it is connected with one of the needles 1, one of the needles 2, one of the needles 1 and so on. In this way 60 a tubular fabric of relatively large diameter may be fabricated in the same circle as a tubular fabric of relatively small diameter.

3, is the needle cylinder externally provided with a series of parallel grooves in 65 which work the needles 1 and provided on top with means for receiving the web holders 4 which are movable pivotally as at 5 and held up to place as by means of an encircling spring 6. Within the needle cylinder 3 is a cylinder 7 rotated as by means of a gear wheel 8. This cylinder 7 carries a projection 9, which operates the web holders. 10, is a cam carried by the cam cylinder 11, which is rotated around the needle cylinder as by means of a gear wheel 12. The cam 10, as well as other cams to be described, are not necessarily shown in the drawings as in appropriate relation, but their operation upon the needles is so well 70 understood that those skilled in the art will understand how they should be placed in order to properly time the movements. For example, the cam 10 would occupy a place on the portion of the needle cylinder which 75 has been removed in drawing the section and this is done for the sake of clearness in illustration. The cam 10 operates upon the bits of the needles 1, which are properly retained in place by means of the encircling spring 80 90 11. Secured to the needle cylinder is a conical ring 13 and this as shown in the drawings is accomplished through the intervention of a ring 14 shrunk or otherwise secured to the ribs which project from the 95 needle cylinder 3.

15, is a revoluble cam ring mounted so as to rotate upon the conical ring 13 and shown as of like conical form. 16, is a pinion for driving the cam ring 15. The cam 17 operates upon jacks 18 and the cam 17, like the cam 10, is not necessarily illustrated in its proper relative position, but is put into the position shown for the sake of clearness. The conical ring 13 is provided with an inclined apron-like portion 19 which is grooved upon its upper face for the reception of the shanks of the needles 2 and of the jacks 18 which work in the same grooves as the needles and are superposed on the needles. The needles 2 have spring bits 105 110 which are arranged to cooperate with the

notched tails of the jacks 18. The cam 17 of the ring 13 works the jacks 18 up and down in the needle grooves of the apron-like portion 19 and when the spring bits of the needles engage the jacks the latter carry the needles up and down, but when the spring bits do not engage the grooves in the tails of the jacks the needles remain down out of action.

10 20, is a thread carrier and it is provided with a projection 21 for opening the latches of the needles 2.

23, are a row of presser bars of which there is one for each of the needles 2. These presser bars 23 work in grooves upon a projection for shelf 24 arranged generally speaking at right angles to the apron 19, so that when a presser bar 23 is pushed inward it serves to disengage the corresponding needle bit from its jack and when the presser bar is released it serves to permit the needle bit to engage its corresponding jack. The presser bars 23 are under control of a drum 25 which is rotated at the proper times and which is provided with projections 26 for pushing in the presser bars 23 so as to free the needles 2 from the jacks 18. As shown the drum is made up of a number of disks strung on a shaft and provided with the 30 projections 26. The drum is turned by means of pawl-and-ratchet connections actuated for example by means of a pawl bar 27 driven by means of a link 28 and eccentric 29 from some shaft as 30, which also 35 drives the gear wheel 31 that turns the shaft which carries the pinions 8, 12 and 16. Two pawls 32 and 33 are shown as arranged upon the bar 27. The pawl 33 cooperates with the loose ratchet wheel 34 that 40 carries a pattern chain 36, and the pawl 32 cooperates with ratchet wheels 35 and 35^a, whereof one 35, is attached to the drum and whereof the other 35^a, is of larger diameter than the first, is loose and is provided at 45 intervals with comparatively deep teeth, so that the pawl drives only the large wheel 35 for some time and until it reaches a deep tooth, when it drives both wheels for a short distance so that the motion of the drum is 50 intermittent. There is also a chain 36 which serves to lift the pawl 32 out of action by operating upon a projection on it. The purpose is to impart by means of the described 55 pawl-and-ratchet connections a proper intermittent and slow motion of rotation to the drum.

At 37 there is shown a lost motion mechanism which is useful in driving the cam ring 11. This consists of a hub secured to 60 the loose pinion 12, and provided with a notch into which projects a pin fast to the driven shaft. At the completion of the work it is desirable to modify the action of the cam 17 and for this purpose a movable or 65 switch cam 38 is to be shifted inward and

afterward outward. To accomplish this the cam 38 is fitted with a head 39 and as it rotates this part 39 comes into contact with one or the other of the arms 40 and 41 mounted upon a vertical movable post 42. The position of this post in its socket 43 is controlled by a lever 44 having a link 45 which is operated upon by a cam 46 carried by the ratchet wheel 35 or some part connected therewith. The cam 17, is a knitting cam and the thread guide is properly positioned in respect to it. The switch cam 38 operates upon the jacks 18, to depress them into position for the release of their needles prior to the receipt of thread so that the needles having been cleared by the riser cam following cam 17 throw off their stitches and go out of action. The switch cam 38 also shifts the jacks so that they clear cam 17, when the needles 2, are not in use.

The mode of operation of the described machine may be explained as follows: The presser bars 23 rest upon the high parts of the drum 25 so that the needles 2 are out of action and this condition of affairs continues while the needles 1 are operated by the cam 10 in the ordinary way so as to take thread from the thread carrier 20 and fabricate a tubular web, for example, the ankle portion of a stocking. When it is desirable to widen this tubular fabric so as to, for example, make it of the proper shape for the calf or leg portion of a stocking the drum comes into such position that one or more of the needles at the center of the group of needles 2 is put into action. In the present instance, one needle at the center of the group of needles 2 is put into action by the operation of the low part between the two high parts on the drum upon the corresponding presser bar 23, as is shown in Fig. 1. When the described low part comes opposite the presser bar 23 the latter shifts outward and permits the corresponding needle bit to be engaged by its jack which brings the needle into action so that it takes thread. This it is permitted to do until it has taken, for example, one stitch, whereupon the high part on the drum is shifted in such a way as to cause the presser bar 23 to again free the needle bit from its jack. In consequence of this the needle remains down out of action, holding a stitch upon it. Several courses of fabric are then knitted by means of the needles 1 whereupon the movement of the drum causes the high part to free the jack and thus the needle bit again engages its jack and comes back into action throwing off the stitch which had formerly been placed upon it and which it held while it was down out of action. The purpose of this is to obviate formation of unsightly holes in the fabric. Thereafter this needle remains in action until the completion of the widened portion of the tube.

Upon the completion of an appropriate number of courses needles of the group 2 upon opposite sides of those that were first put into action, are brought into action in the manner described.

To recapitulate for the sake of clearness, one or more needles at the center of the group of needles 2, come into action, take a stitch, go down out of action and hold that 10 stitch for several courses, whereupon it or they is or are again brought into action throwing off the stitch previously placed upon it or them. After the completion of an appropriate number of courses, say ten 15 or fifteen, one or more needles on opposite sides of these center needles are permitted to take a stitch or stitches, to then go down out of action and hold this stitch or stitches until the completion of several courses where- 20 upon they again go into action and this is repeated until all of the needles 2 have been successively brought into action, whereupon the widened tube may be knitted to any de- 25 sired length. Upon the completion of the tube the switch cam 38 is brought into action through the instrumentality of the parts connected with the post 42 and the head 39. The detent 47 serves to prevent undesirable motions of the head and parts 30 connected therewith.

It will be obvious to those skilled in the art to which my invention appertains that modifications may be made in details without departing from the spirit thereof, hence 35 the invention is not limited further than the prior state of the art may require, but

Having thus described the nature and objects of my invention what I claim as new and desire to secure by Letters Patent is— 40 1. A circular knitting machine having in combination a cylinder and an inclined apron-like portion grooved upon its upper face and extending part way around the cylinder, each equipped with a set of needles those of one set being disposed at an acute angle in respect to those of the other set, whereby the knocking-over point of the two sets of needles are in different circles, and means for knitting upon said needles to 45 produce a seamless, tubular, plain web of varying diameter.

2. A knitting machine provided with a circular group of needles and with a second group of needles arranged intermediate of 50 and at an acute angle with the needles of the first group and disposed operatively in a different knocking-over circle from the first mentioned needles, the hooks of all the needles being arranged in the same direction.

3. In a knitting machine the combination of a needle cylinder and its needles, a conical ring applied to the needle cylinder and provided with inclined needle grooves and a 55 revolute cam ring, needles arranged in said

inclined grooves, jacks detachably connected with the last mentioned needles and operatively arranged in respect to the cam ring, and means for detaching the jacks and the last mentioned needles, substantially as de- 70 scribed.

4. In a knitting machine the combination with a needle cylinder and its needle and thread carrier, of a group of needles arranged at an inclination to the first mentioned needles and of a latch opening device carried by the thread carrier and arranged to coöperate with the last mentioned needles, substantially as described.

5. A knitting machine having a needle cylinder and its needles in combination with a group of needles arranged at an inclination to the first mentioned needles, jacks for actuating said group of needles, devices for disconnecting said jacks, and a cam surface 80 for actuating said devices, substantially as described.

6. In a knitting machine the combination of a circular group of needles, an inclined group of needles, jacks detachably connected with the last mentioned needles, devices for detaching the jacks, and a drum provided with a cam surface for operating said devices, substantially as described.

7. The combination with a cylindrical 95 knitting machine of an inclined apron having needle grooves and needles and jacks and provided with grooves for the reception of presser bars, presser bars adapted to disconnect the jacks, and a cam surface for operating the presser bars, substantially as described.

8. The combination with a circular knitting machine of an inclined apron provided with grooves, jacks, needles arranged in said 105 grooves and provided with spring bits for detachably engaging the jacks, presser bars arranged to operate on the spring bits, and cam surfaces for operating the presser bars, substantially as described.

9. The combination in a circular knitting machine of a circular group of needles and their actuating mechanism, a group of widening needles arranged intermediate of and at an inclination to the first mentioned 115 needles and their actuating mechanism, and devices for bringing the widening needles progressively from the center toward the edges of the group thereof into action so as to receive a loop or loops, then 120 out of action and finally into action, and means for putting all the widening needles automatically out of action, substantially as described.

10. The combination of a member having 125 a needle groove, a spring bit arranged in the groove, a jack arranged in the same groove as and adapted to ride on the needle and detachable from the latter, the spring bit of the needle projecting beyond the hook 130

part of the jack, and means arranged at the limit of the travel of the spring bit for compressing the spring bit to free it from the jack.

5 11. In combination a bed having needle grooves, spring bit needles arranged in the grooves and separate jacks riding on the needles and of less length than the spring bits whereby the latter are accessible, substantially as described.

10 12. A circular knitting machine having, in combination a cylinder and dial, each equipped with a set of needles, those of one set being disposed at an acute angle in respect to those of the other set, and means for knitting upon said needles to produce a seamless, tubular, plain web of varying diameter.

13. A circular knitting machine having, 20 in combination a cylinder and dial, each equipped with a set of needles, those of one set being disposed at an acute angle in respect to those of the other set, and means for knitting upon said needles to produce a 25 seamless, tubular, plain web of varying diameter with heels and toes upon the narrow portions of said web.

14. A circular knitting machine having, 30 in combination a cylinder and dial, each equipped with a set of needles, those of one set being disposed at an acute angle in respect to those of the other set and both sets drawing stitches to the same face of the web, and means for knitting upon said 35 needles to produce a seamless, tubular web of varying diameter.

15. A circular knitting machine having, 40 in combination a cylinder and dial, each equipped with a set of needles, those of one set being disposed at an acute angle in respect to those of the other set and both sets drawing stitches to the same face of the web, and means for knitting upon said needles to produce a seamless, tubular web of varying 45 diameter and for knitting upon needles of one set only to produce seamless pockets.

16. A circular knitting machine for producing shaped webs, said machine having, in combination, a cylinder and dial, each 50 equipped with a set of needles, those of one set being disposed at an acute angle in respect to those of the other set, and both sets drawing stitches to the same face of the web, and means for knitting successively upon 55 the narrow web needles and upon the latter and the wide web needles to produce, in each case, a seamless, tubular web.

17. A circular knitting machine for producing shaped webs, said machine having, 60 in combination, a cylinder and dial, each equipped with a set of needles, those of one set being disposed at an acute angle in respect to those of the other set, and both sets drawing stitches to the same face of the web, 65 and means for knitting successively upon

the narrow web needles and upon the latter and a varying number of the wide web needles to produce, in each case, a seamless, tubular web.

18. A circular knitting machine for producing shaped webs, said machine having, in combination, a cylinder and dial, each equipped with a set of needles, those of one set being disposed at an acute angle in respect to those of the other set, and both sets 70 drawing stitches to the same face of the web, and means for knitting successively upon the narrow web needles and upon the latter and a varying number of groups of the wide web needles to produce, in each case, a seam- 80 less, tubular web.

19. A circular knitting machine for producing shaped webs, said machine having, in combination, a cylinder and dial, each equipped with a set of needles, those of one 85 set being disposed at an acute angle in respect to those of the other set, and both sets drawing stitches to the same face of the web, and means for knitting successively upon the narrow web needles and upon the latter and 90 a progressively increasing number of widening needles to produce, in each case, a seamless, tubular web.

20. A circular knitting machine for producing shaped webs, said machine having, 95 in combination, a cylinder and dial, each equipped with a set of needles, those of one set being disposed at an acute angle in respect to those of the other set, and both sets drawing stitches to the same face of the web, 100 and means for knitting successively upon the narrow web needles and upon the latter and a progressively increasing number of groups of widening needles to produce, in each case, a seamless tubular web.

105 21. A circular knitting machine having, in combination, a cylinder and dial, each equipped with a set of needles, those of one set being disposed at an acute angle in respect to those of the other set, and both sets drawing stitches to the same face of the web, 110 and means for knitting upon the cylinder needles to produce seamless, tubular web of relatively small diameter, and simultaneously upon both cylinder and dial needles 115 to produce seamless, tubular web of greater diameter.

120 22. A circular knitting machine having, in combination, a cylinder and dial, each equipped with a set of needles, those of one set being disposed at an acute angle in respect to those of the other set, and both sets drawing stitches to the same face of the web, and means for knitting upon the cylinder needles to produce seamless, tubular web of relatively small diameter, and simultaneously upon said cylinder needles and upon a varying number of the dial needles to produce 125 seamless, tubular web of greater diameter.

23. A circular knitting machine having, in combination a cylinder and dial, each equipped with a set of needles, those of one set being disposed at an acute angle in respect to those of the other set, and both sets drawing stitches to the same face of the web, means for putting into action a progressively increasing number of dial needles, and means for knitting upon the cylinder 10 needles to produce seamless, tubular web of relatively small diameter, and simultaneously upon said cylinder needles and upon the progressively increasing number of the dial needles to produce seamless, tubular 15 web of progressively increasing diameter.

24. A circular knitting machine having, in combination, a cylinder and dial, each equipped with a set of needles those of one set being disposed at an acute angle in respect to those of the other set, and both sets drawing stitches to the same face of the web, means for putting into action a varying number of groups of dial needles, and means for knitting upon the cylinder needles 20 to produce seamless, tubular web of relatively small diameter and simultaneously upon said cylinder needles and upon the varying number of groups of the dial needles to produce seamless, tubular web of 25 greater diameter.

25. A circular knitting machine having, in combination, a cylinder and dial, each equipped with a set of needles, those of one set being disposed at an acute angle in respect to those of the other set, and both sets drawing stitches to the same face of the web, means for putting into action successively introduced groups of dial needles, and means for knitting upon the cylinder 30 needles to produce seamless, tubular web of relatively small diameter and simultaneously upon said cylinder needles and upon the successively introduced groups of the dial needles to produce seamless, tubular web of progressively increasing diameter.

26. A circular knitting machine having,

in combination, a cylinder and dial, each equipped with a set of needles, those of one set being disposed at an acute angle in respect to those of the other set, and both sets drawing stitches to the same face of the web, a yarn guide, cams for actuating the needles to cause them to knit, and means for operating needles of one set to place them under or out of control of their knitting cams.

27. A circular knitting machine having, in combination, a cylinder and dial, each equipped with a set of needles those of one set being disposed at an acute angle in respect to those of the other set, and both sets drawing stitches to the same face of the web, a yarn guide, cams for actuating the needles to cause them to knit, and means for operating needles of one set in groups to place them under or out of control of their knitting cams.

28. A circular knitting machine having, in combination, a cylinder and dial, each equipped with a set of needles those of one set being disposed at an acute angle in respect to those of the other set, and both sets drawing stitches to the same face of the web, and means for knitting upon said needles to produce a shaped, seamless, tubular web, the needle-actuating devices being so disposed that the narrow web needles do not draw stitches in advance of the wide web needles.

29. A circular knitting machine having a cylinder provided with needles, and a dial likewise provided with needles disposed to draw stitches to the same face of the fabric as the cylinder needles and occupying an acute angle in respect thereto, said dial needles having a bearing below the top of the cylinder but being free from contact with said cylinder at the top.
